SCREW OPERATED JAR CAP WRENCH

Joseph W. Fay, Villa Park, Ill., assignor of one-half to Irwin J. Mendels, Evanston, Ill.

Application September 23, 1946, Serial No. 698,641

6 Claims. (Cl. 81—3.42)

1

This invention relates, in general, to screw operated jar cap wrenches, and has particular relation to an improved device for loosening and tightening screw caps, screw covers and the like.

While I shall describe hereinafter in connection with the drawing the use of the device in connection with a relatively large screw cap for a relatively large jar, it is to be understood that the device of the present invention may be used on screw caps of widely different sizes up to larger sizes and down to the screw caps used on relatively small drug bottles.

In prior devices of the sort with which the present invention is concerned, the inner jaw has been loose or free of the handle of the device and in position adjacent the inner end of the handle for rectilinear movement only into gripping engagement with the cap by rotation of the handle. Where gripping engagement of the inner jaw with the cap is secured solely by rectilinear movement, the desired fast and firm hold on the cap is not at all times assured, particularly where the outer periphery of the screw-threaded flange of the cap is of a form not to be securely gripped and firmly held by such action.

One of the main objects of the present invention is to provide an improved cap loosening and tightening device with which a better and more secure and firm gripping engagement is assured with the cap, regardless of the form of the outer periphery of the screw-threaded flange of the cap.

Another and more specific object of the invention is to provide in a cap loosening or tightening device of the class described an inner jaw in the form of a round, sharp spinner, which, in application of the device, is adapted to spin a groove into the outer periphery of the screw-threaded flange of the cap to assure firm and secure gripping engagement with the cap for loosening or tightening the same.

Another object of the invention is to provide a cap loosening or tightening device of the character described having the novelty and advantages set forth and characterized by its simplicity in construction, its economy in manufacture, and its effectiveness in use for accomplishing the desired results.

Further objects and advantages of the invention will appear from the following detailed description, taken in connection with the accompanying drawing in which:

Figure 1 is a top plan view of a jar with the cap loosening or tightening device of the present invention applied to the cap or cover thereof, the cover being shown partially broken away and in section;

Figure 2 is a fragmentary side view of the jar

2

with the cap loosening or tightening device engaged with the cap or cover of the jar;

Figure 3 is a transverse sectional view taken on the line 3—3 of Figure 2;

Figure 4 is a sectional view taken longitudinally through the cap loosening and tightening device substantially on the line 4—4 of Figure 1;

Figure 5 is a fragmentary detail section taken on the line 5—5 of Figure 2; and

Figure 6 is a fragmentary detail section taken on the line 6—6 of Figure 3.

Referring now to the drawing, in the embodiment of the invention selected for illustration, 15 the device comprises a stem 1 threaded at 2 and having a cap gripping jaw 3 fixed at 4 on the outer end of the stem.

While the details of the jaw 3 and its attachment at 4 to the stem 1 may vary, I have shown 20 this jaw of arcuate form to follow in general the circular outer periphery of the screw-threaded flange 5 of the screw cap 6 when the device is applied to the cap. The jaw 3 has circumferentially spaced teeth 7, the inner ends 25 of which are preferably sharp to indent the outer periphery of the cap as shown at 8 when the device is applied to the cap in order to assure firm gripping engagement with the cap. For securing the jaw 3 on the outer end of the 30 stem, the outer end of the stem may be reduced at 9 and passed through an opening in the jaw 3 and riveted over at 10, but this, of course, may vary.

A spinner 11 is screwed on the stem 1 at 12, 35 and has a round sharp edge 13 adapted to spin a groove into the outer periphery of the flange 5 of the cap 6 by screwing the spinner 11 along the stem 1. This assures a more secure and firm gripping engagement with the cap 6 regardless 40 of the form and size of the outer periphery of the screw-threaded flange of the cap.

The handle 14 is preferably formed of wood, although it may be formed of plastic or any other suitable material. It has an axial opening 45 15 through which the stem 1 is adapted to extend for rotation of the handle about the stem. For the purpose of fixedly securing the handle 14 to the spinner 11 so that the spinner will be rotated and screwed along the stem 1 by rotation of the handle, the spinner 11 may, for example, be provided with an integral tubular extension 16 fitting into an enlarged axial opening 17 at the inner end of the handle 14. The outer periphery of the tubular extension 16 has

55 longitudinal or other serrations 18 engaging into the inner periphery of the opening 17 to secure the spinner 11 to the handle 14 for rotation therewith. The inner end of the handle 14 is shown fixedly abutting the spinner 11 at 19.

The threads 2 on the stem 1 terminate at 23 at a distance from the end of the stem to limit the screwing movement of the handle and spinner from the end of the stem.

The spinner 11 is shown of one piece or unitary form, but it is to be understood that it may be made out of two or more pieces riveted or otherwise secured together. The particular manner of rigidly securing the handle 14 to the spinner 11 may also be varied.

In use, the device is applied to the desired screw cap by grasping the handle 14 and turning it to screw the spinner 11 and handle 14 as a unit outwardly along the stem 1 to adjust the space between the jaw 3 and the spinner 11 for the reception of the screw-threaded flange 5 of the cap diametrically therebetween. The device is then placed on the cap 6 as shown in Figures 1 and 2, with the stem 1 against and extending diametrically across the top of the cap and with the jaw 3 and spinner 11 positioned to grip the flange of the cap between them.

The handle 14 is then turned in the opposite direction to screw the spinner 11 toward the side of the cap to grip the cap between the spinner and the jaw 3. As previously stated, as the spinner 11 is engaged with the cap, its screwing action along the stem 1 spins with great force a groove into the outer periphery of the flange 5. This group is shown partially in section at 20 in Figure 6. At the same time, the jaw 3 is brought into gripping engagement with the diametrically opposite side of the cap 6, the teeth 7 being adapted to indent the outer periphery of the flange 6 as shown at 8. In this way, firm and secure gripping engagement with the cap is secured regardless of the form or size of the cap.

With the device thus applied to the cap, the jar, indicated fragmentarily at 22, or the bottle or the like is firmly gripped in one hand and, by the use of the handle 14, leverage is obtained to enable loosening or removal of the cap 6 even though it is very tight or frozen into place. The device may also be used in a similar manner to tighten the cap. One form of thread in the threaded flange 5 of the cap is shown in section at 21 in Figure 6.

The embodiment of the invention shown in the drawing is for illustrative purposes only, and it is to be expressly understood that such drawing and the accompanying specification are not to be construed as a definition of the limits or scope of the invention, reference being had to the appended claims for that purpose.

I claim:

1. In a loosening and tightening device for screw caps, in combination, a threaded stem, a cap gripping jaw fixed on the outer end of said stem, a round spinner having a sharp peripheral knife edge and internal threads screwed on said stem, a handle fixedly secured to said spinner and rotatable about the axis of said stem to screw the spinner along the stem to adjust the space between said jaw and said spinner for the reception of a cap therebetween, said spinner in the application of the device to a cap being adapted to be screwed along the stem by rotation of said handle to spin a groove into the outer periphery of the screw-threaded flange of the cap to assure firm gripping engagement with the cap.

2. In a loosening and tightening device for screw caps, in combination, a threaded stem, a

cap gripping jaw fixed on the outer end of said stem, a handle, and a round spinner having a sharp peripheral knife edge fixedly secured to the inner end of the handle, said spinner having internal threads engaging the threads on the stem whereby said handle and spinner are screwed as a unit on said stem and adapted by screwing along the stem to adjust the space between said jaw and said spinner for the reception of a cap therebetween, said spinner in the application of the device to a cap being adapted to be screwed along the stem by rotation of the handle to spin a groove into the outer periphery of the screw-threaded flange of the cap to assure firm gripping engagement with the cap.

3. In a loosening and tightening device for screw caps, in combination, a threaded stem, a cap gripping jaw fixed on the outer end of said stem, a handle, and a round spinner having a sharp peripheral knife edge fixedly secured to the inner end of the handle, said spinner having internal threads engaging the threads on the stem whereby said handle and spinner are screwed as a unit on said stem and adapted by screwing along the stem to adjust the space between said jaw and said spinner for the reception of a cap therebetween, said spinner in the application of the device to a cap being adapted to be screwed along the stem by rotation of the handle to spin a groove into the outer periphery of the flange of the cap to assure firm gripping engagement with the cap, the threads on said stem terminating at a distance from the outer end of the stem to limit the screwing movement of the handle from the end of the stem.

4. In a loosening and tightening device for screw caps, in combination, a threaded stem, a spinner having internal threads screwed on said stem and having a round sharp peripheral knife edge positioned for presentation to the cap when the device is applied to the cap and adapted to spin a groove into the outer periphery of the screw-threaded flange of a screw cap by screwing said spinner along said stem, and a cooperating jaw fixed on the outer end of the threaded stem for engaging the flange of the cap in substantially diametrically opposite position.

5. A loosening and tightening device for screw caps according to claim 1, wherein the jaw on the outer end of the threaded stem is of arcuate form and has circumferentially spaced sharp teeth adapted to indent the outer periphery of the screw-threaded flange of the cap to assure firm gripping engagement with the cap.

6. A loosening and tightening device for screw caps according to claim 2, wherein the round sharp spinner has a tubular extension fitting into an opening in the adjacent end of the handle and provided with serrations on its outer periphery engaging in the inner periphery of said opening to secure the spinner to the handle for rotation therewith.
